RELIGIOUS DISPLAY ORNAMENT

Robert Hoffman, San Francisco, Calif.

Application November 14, 1955, Serial No. 38,871

Term of patent 14 years

(Cl. D29—23)

I claim:

The ornamental design for a religious display ornament, as shown.
